Primary Examiner — George D. Kirschbaum*Assistant Examiner* — Clese Moore, Jr.(74) *Attorney, Agent, or Firm* — Dunlap, Bennett & Ludwig PLLC(57) **CLAIM**

The ornamental design for a bike rack, as shown and described.

DESCRIPTION

FIG. 1 is a top front perspective view of a bike rack;
 FIG. 2 is a front elevation view thereof;
 FIG. 3 is a rear elevation view thereof;
 FIG. 4 is a right elevation view thereof, the left elevation view being a mirror image thereof;
 FIG. 5 is a top plan view thereof;
 FIG. 6 is a bottom plan view thereof; and,
 FIG. 7 is a top front perspective view of the bike rack shown in use.
 The broken lines showing a bike in FIG. 7 depicts environmental subject matter that forms no part of the claimed design.
